(57) **ABSTRACT**

A transport device for transporting a roll-shaped recording medium includes: a pair of roll retainers that are attached to both sides of a roll portion of the roll-shaped recording medium; a pair of spindles that are engaged with the roll retainers to support the roll portion; a transport roller that transports the roll-shaped recording medium drawn out from the roll portion while pinching the roll-shaped recording medium; and a positioning mechanism that rotates the roll portion supported by the spindles in a direction in which tension is applied to the drawn roll-shaped recording medium to move the roll portion to one side in a longitudinal direction such that a reference edge of the roll-shaped recording medium comes into contact with a reference position, thereby positioning the reference edge of the roll-shaped recording medium.

TRANSPORT DEVICE FOR TRANSPORTING
ROLL-SHAPED RECORDING MEDIUM AND
RECORDING APPARATUS

BACKGROUND

1. Technical Field

The present invention relates to a transport device for transporting a roll-shaped recording medium having a function of positioning the roll-shaped recording medium and a recording apparatus.

2. Related Art

Hereinafter, an ink jet printer, which is an example of a recording apparatus, will be described. Among the ink jet printers, there is a large ink jet printer capable of ejecting ink onto a recording medium having a large size, such as an A1+ (extension) size or a B0+ (extension) size, to perform recording. The large ink jet printer generally uses roll-shaped recording media having a roll width of 24 inches (about 610 mm), 36 inches (about 914 mm), or 44 inches (about 1118 mm), and a roll length of 10 m to 45 m. In addition, various kinds of roll-shaped recording media have been used. For example, roll-shaped recording media made of different materials, such as paper or a film, roll-shaped recording media having high rigidity, such as resin-coated photo paper, and roll-shaped recording media having low rigidity, such as plain paper, have been used.

In the ink jet printer, a printer body is provided with a roll holder that sets a roll-shaped recording medium (hereinafter, referred to as a roll sheet). In the related art, a plurality of roll shafts having different lengths are used to correspond to the roll widths of roll sheets. The roll shaft is inserted into a roll core of the roll sheet and then the roll sheet is set to the roll holder. However, the operation of setting the roll sheet needs to ensure a large working space, or the setting operation becomes complicated. In addition, when a long roll shaft is used, the roll shaft is likely to be bent, which causes the roll sheet to be obliquely transported.

Therefore, JP-A-2007-261754 discloses a device for supporting a roll-shaped recording medium. In the device for supporting a roll-shaped recording medium, flange members, serving as roll retainers, are attached to both sides of the roll-shaped recording medium. Then, first, a driven flange member is mounted to a second holder member that is disposed on the driven side of the roll holder and can be rotated in a roll width direction. Then, the second holder member is moved together with the roll sheet to a first holder member that is disposed on the driving side of the roll holder to mount the driving flange member attached to the roll sheet to the first driving holder member, thereby setting the roll sheet to the roll holder.

According to the device for supporting a roll-shaped recording medium having the above-mentioned structure, the problems of the related art, such as a large working space, a complicated setting operation, and the oblique transport of a roll sheet due to the bending of a roll shaft, are solved.

However, when the roll sheet set to the second holder member is moved to be set to the first holder member, it is difficult to sufficiently move the roll sheet and backlash is likely to occur between the driving flange member and the first holder member. When the roll sheet is drawn while the backlash occurs, the position of the reference edge of the roll sheet is not determined, and an image is not recorded at a desired position on the roll sheet.

SUMMARY

An advantage of some aspects of the invention is that it provides a transport device for transporting a roll-shaped

2

recording medium capable of performing a general operation to automatically dispose the reference edge of the roll-shaped recording medium at a regular reference position, for example, during the drawing of the roll-shaped recording medium, even when the set position of a roll portion of the roll-shaped recording medium is insufficient, and a recording apparatus including the transport device for transporting a roll-shaped recording medium.

According to a first aspect of the invention, there is provided a transport device for transporting a roll-shaped recording medium. The transport device includes: a pair of roll retainers that are attached to both sides of a roll portion of the roll-shaped recording medium; a pair of spindles that are engaged with the roll retainers to support the roll portion; a transport roller that transports the roll-shaped recording medium drawn out from the roll portion while pinching the roll-shaped recording medium; and a positioning mechanism that rotates the roll portion supported by the spindles in a direction in which tension is applied to the drawn roll-shaped recording medium to move the roll portion to one side in a longitudinal direction such that a reference edge of the roll-shaped recording medium comes into contact with a reference position, thereby positioning the reference edge of the roll-shaped recording medium.

According to the above-mentioned aspect, even when the set position of the roll portion of the roll-shaped recording medium is insufficient, it is possible to perform a general operation to automatically dispose the reference edge of the roll-shaped recording medium at a regular reference position, for example, during the drawing of the roll-shaped recording medium.

According to a second aspect of the invention, there is provided a transport device for transporting a roll-shaped recording medium. The transport device includes: a driving roll retainer and a driven roll retainer that are attached to both sides of a roll portion of the roll-shaped recording medium; a driving spindle and a driven spindle that are engaged with the driving roll retainer and the driven roll retainer to support the roll portion; a driving supporting mechanism and a driven supporting mechanism that support the driving spindle and the driven spindle; a spindle driving source that rotates the driving spindle forward and backward; a moving mechanism that moves the driven supporting mechanism toward the driving supporting mechanism such that the driving spindle and the driven spindle support the roll portion; a transport roller that transports the roll-shaped recording medium drawn out from the roll portion while pinching the roll-shaped recording medium; and a positioning mechanism that positions a reference edge of the roll-shaped recording medium by operating the transport roller or the spindle driving source or drawing out the roll-shaped recording medium from the roll portion to rotate the roll portion supported by the driving spindle and the driven spindle in a direction in which tension is applied to the drawn roll-shaped recording medium, thereby moving the roll portion to the driving spindle such that the reference edge of the roll-shaped recording medium comes into contact with a reference position.

According to the above-mentioned aspect, any of the following general operations are performed before recording: an operation of moving the driven supporting mechanism to the driving supporting mechanism to support the roll portion with the driving spindle and the driven spindle, drawing the start point of the roll-shaped recording medium from the roll portion, and transporting the recording medium using the transport roller; and an operation of rotating the spindle in the winding direction to apply tension to the roll-shaped recording medium between the transport roller and the roll portion.

Therefore, the set position of the roll portion of the roll-shaped recording medium is automatically corrected, and it is possible to move the reference edge of the roll-shaped recording medium to the regular reference position.

According to a third aspect, the transport device for transporting a roll-shaped recording medium according to the first or second aspect may further include: engaging portions that are provided in the driving spindle and the driven spindle; and engaged portions that are provided in the driving roll retainer and the driven roll retainer and are engaged with the engaging portions of the driving and driven spindles such that power can be transmitted. The positioning mechanism may be a cam structure that is provided between the engaged portion of the driving roll retainer and the engaging portion of the driving spindle.

According to the above-mentioned aspect, since the positioning mechanism is a cam structure that is provided between the engaged portion of the driving roll retainer and the engaging portion of the driving spindle, the driving roll retainer is moved toward the driving spindle to be set to the driving spindle. In this way, a cam structure is obtained. That is, it is possible to reduce the number of parts of the positioning mechanism and simplify the structure of the positioning mechanism.

According to a fourth aspect of the invention, in the transport device for transporting a roll-shaped recording medium according to the third aspect, the cam structure may have a cam including a cam follower that is formed on an inner circumferential surface of the driving roll retainer so as to extend inward and a cam groove that is formed in an outer circumferential surface of the engaging portion. The cam groove may include: a guide portion that guides the cam follower into the cam groove; a drawing portion that draws the cam follower into the cam groove such that the reference edge of the roll-shaped recording medium reaches the reference position when the roll portion is rotated in the direction in which tension is applied; and a straight portion that enables the cam follower to be withdrawn from the cam groove when the roll portion is rotated in a direction in which the tension is removed.

According to the above-mentioned aspect, it is possible to form a cam structure using the existing engaging structure that is provided between the engaged portion of the driving roll retainer and the engaging portion of the driving spindle in order to transmit the rotation of the spindle driving source to the roll portion of the roll-shaped recording medium. The guide portion, the drawing portion, and the straight portion provided in the cam groove make it possible to perform an operation of smoothly inserting the cam follower into the cam groove, an operation of correcting the set position of the roll portion (moving the roll portion to the regular reference position) and holding the set position, and an operation of smoothly withdrawing the cam follower from the cam groove.

The transport device for transporting a roll-shaped recording medium according to any one of the first to fourth aspects may further include: a tension generating unit that generates a constant tension to the roll-shaped recording medium between the transport roller and the roll portion regardless of a variation in the roll diameter of the roll portion.

According to the above-mentioned aspect, even when the roll diameter of the roll portion varies, the set tension of the roll-shaped recording medium between the transport roller and the roll portion is maintained to be constant. Therefore, it is possible to improve the transport accuracy of a roll-shaped recording medium. As a result, it is possible to move the

reference edge of the roll-shaped recording medium to the regular reference position and improve recording quality.

According to a sixth aspect of the invention, a recording apparatus includes: the roll-shaped recording medium transport device according to any one of the first to fifth aspects that transports a roll-shaped recording medium to a recording position while drawing out the roll-shaped recording medium; and a recording device that ejects ink onto a recording surface of the roll-shaped recording medium transported to the recording position to perform desired recording.

According to the above-mentioned aspect, a general operation is performed to automatically correct the set position of a roll-shaped recording medium before recording, thereby moving the reference edge of the roll-shaped recording medium to the regular reference position. In addition, the set tension of the roll-shaped recording medium between the transport roller and the roll portion is maintained to be constant, regardless of a variation in the roll diameter of the roll portion. Therefore, it is possible to improve the positional accuracy of the roll-shaped recording medium in the roll width direction and the transport accuracy thereof. As a result, it is possible to improve recording quality.

BRIEF DESCRIPTION OF THE DRAWINGS

The invention will be described with reference to the accompanying drawings, wherein like numbers reference like elements.

FIG. 1 is a perspective view illustrating the outward appearance of an ink jet printer.

FIG. 2 is a side cross-sectional view illustrating the ink jet printer from which a body cover is removed.

FIG. 3 is a side cross-sectional view schematically illustrating the internal structure of the ink jet printer.

FIG. 4 is a perspective view illustrating a roll sheet that is set to a driving spindle.

FIG. 5 is an enlarged perspective view illustrating the periphery of a driven spindle of a roll holder.

FIG. 6 is an enlarged perspective view illustrating the periphery of the driving spindle of the roll holder.

FIG. 7 is an exploded perspective view illustrating the roll sheet and a roll rewinding mechanism.

FIG. 8 is a front cross-sectional view illustrating a transport device for transporting a roll-shaped recording medium according to an embodiment of the invention.

FIGS. 9A to 9C are front cross-sectional views sequentially illustrating the insertion or removal of the roll sheet into or from a driving side.

FIG. 10 is a side cross-sectional view illustrating the transport device for transporting a roll-shaped recording medium according to the embodiment of the invention.

FIG. 11 is a flowchart illustrating the first half of a control process of setting the torque of a spindle motor.

FIG. 12 is a flowchart illustrating the second half of the control process of setting the torque of the spindle motor.

DESCRIPTION OF EXEMPLARY EMBODIMENTS

Hereinafter, a transport device for transporting a roll-shaped recording medium and a recording apparatus including the transport device for transporting a roll-shaped recording medium according to an embodiment of the invention will be described. First, the outline of the overall structure of an ink jet printer 100, which is an example of the recording apparatus according to the embodiment of the invention, will be described. The ink jet printer 100 according to this embodiment

ment is a large ink jet printer that can perform recording on a recording surface of a large sheet-shaped recording medium (hereinafter, referred to as a cut sheet) having, for example, an A3+ (extension) size or more or a large roll-shaped recording medium (hereinafter, referred to as a roll sheet) P having, for example, an A1+ (extension) size or a B0+ (extension) size.

FIG. 1 is a perspective view illustrating the outward appearance of the ink jet printer having a body cover attached thereto, and FIG. 2 is side cross-sectional view illustrating the ink jet printer from which the body cover is removed. FIG. 3 is a side cross-sectional view schematically illustrating the internal structure of the ink jet printer.

The ink jet printer 100 shown in FIGS. 1 to 3 includes a printer body 3, which is an example of a recording apparatus body. As shown in FIG. 1, the printer body 3 is covered with a body cover 2. A roll holder H that holds a roll sheet P in the horizontal direction is provided on the rear upper side of the printer body 3. A pair of left and right spindles 4R and 4L are provided in the roll holder H, and the roll sheet P held by roll retainers 5R and 5L including a pair of left and right flange portions 6R and 6L can be rotated integrally with the spindles 4R and 4L. In addition, a cartridge holder 8 having a plurality of cartridge slots capable of individually accommodating color ink cartridges is provided at, for example, the left end of the front surface of the printer body 3.

A control panel 9 for inputting various operation instructions is provided at, for example, the right end of the front surface of the ink jet printer 100. In addition, a transport guide plate 11 is provided in the printer body 3 so as to be inclined downward at an angle of about 60°, and guides the roll sheet P that is held in the horizontal direction by the spindles 4R and 4L such that the roll sheet P can be transported to the front lower side, which is the drawing direction A of the roll sheet P. The printer body 3 includes a transport device 1 that transports the roll sheet P, which is a roll-shaped recording medium according to the invention, downward toward a recording position 26 while drawings out the roll sheet P, and a recording device 12 that ejects ink onto a recording surface of the roll sheet P transported to the recording position 26 to perform desired recording.

The recording device 12 is provided at an obliquely upward position with respect to the recording position 26, and includes a recording head 13 that ejects ink to perform recording and a carriage 10 that has the recording head 13 mounted thereon and is reciprocated in a roll width direction C, which is a scanning direction. A platen 28 that supports the rear surface of the roll sheet P to define a gap PG between the roll sheet and the recording head 13 is provided below the recording position 26.

Embodiments

Next, the transport device 1 for transporting a roll-shaped recording medium according to an embodiment of the invention that can be applied to the ink jet printer 100 having the above-mentioned structure will be described in detail with reference to the accompanying drawings.

FIG. 4 is a perspective view illustrating the roll sheet supported by a driving spindle and a driven spindle. FIG. 5 is an enlarged perspective view illustrating the periphery of the driven spindle of the roll holder. FIG. 6 is an enlarged perspective view illustrating the periphery of the driving spindle of the roll holder. FIG. 7 is an exploded perspective view illustrating the roll sheet and a roll rewinding mechanism. FIG. 8 is a longitudinal cross-sectional view illustrating the transport device that transports a roll-shaped recording medium according to the embodiment of the invention. FIGS.

9A to 9C are longitudinal cross-sectional views illustrating the insertion and removal of the roll sheet into or from the driving spindle. FIG. 10 is a diagram schematically illustrating the relationship between components of the transport device for transporting a roll-shaped recording medium according to the embodiment.

The transport device 1 for transporting a roll-shaped recording medium according to this embodiment basically includes: the driving roll retainer 5R and the driven roll retainer 5L that are attached to both sides of a roll portion 31 of the roll sheet P; the driving spindle 4R and the driven spindle 4L that are respectively engaged with the driving roll retainer 5R and the driven roll retainer 5L to support the roll portion 31; a driving supporting mechanism 14R and a driven supporting mechanism 14L that support the driving spindle 4R and the driven spindle 4L, respectively; a spindle motor 30 that rotates the driving spindle 4R forward and backward; and a moving mechanism 65 that moves the driven supporting mechanism 14L toward the driving supporting mechanism 14R such that the driving spindle 4R and the driven spindle 4L support the roll portion 31.

In this embodiment, the transport device 1 for transporting a roll-shaped recording medium further includes: a transport roller 21, which is a transport member for transporting the roll sheet P, including a transport driving roller 19 and a transport driven roller 20 that transport the roll sheet P drawn out from the roll portion 31 with the roll sheet interposed therebetween; and a tension generating member 29 that generates a constant tension F to the roll sheet P between the transport roller 21 and the roll portion 31 without being affected by the roll diameter D of the roll portion 31.

The transport device 1 for transporting a roll-shaped recording medium according to this embodiment is characterized in that it includes a positioning mechanism 60 that operates the transport roller 21 or the spindle motor 30 or drawing out the roll sheet P from the roll portion 31 to rotate the roll portion 31 supported by the driving spindle 4R and the driven spindle 4L in the direction in which tension is applied to the drawn roll sheet P, thereby moving the roll portion 31 to the driving spindle 4R such that the reference edge E of the roll sheet P comes into contact with a pressing reference position 64R. In this way, the positioning mechanism 60 positions the reference edge of the roll sheet.

The transport device 1 further includes: engaging portions 61R and 61L that are provided in the driving spindle 4R and the driven spindle 4L, respectively; and engaged portions 57R and 57L that are respectively provided in the driving roll retainer 5R and the driven roll retainer 5L and are respectively engaged with the engaging portions 61R and 61L of the spindles 4R and 4L such that power can be transmitted. The positioning mechanism 60 may be a cam structure 60 (which has the same reference numeral as the positioning mechanism 60) that is provided between the engaged portion 57R of the driving roll retainer 5R and the engaging portion 61R of the driving spindle 4R.

The driving roll retainer 5R and the driven roll retainer 5L include core portions 53R and 53L that are inserted into a roll core 7 of the roll sheet P and the flange portions 6R and 6L that come into contact with both end surfaces of the roll sheet P to hold the roll sheet P, respectively. The core portions and the flange portions are integrally formed. Small-diameter insertion grooves 56R and 56L into which the leading ends 55R and 55L of the spindles 4R and 4L are inserted and large-diameter engaged portions 57R and 57L that communicate with the insertion grooves 56R and 56L are formed at the

centers of the outer end surfaces **54R** and **54L** of the roll retainers **5R** and **5L** provided in the flange portions **6R** and **6L**, respectively.

For example, three engaging protrusions **58R** and three engaging protrusions **58L** are provided at the same pitch on the inner circumferential surfaces of the engaged portions **57R** and **57L** so as to protrude inward. The driving engaging protrusions **58R** also serve as cam followers **58R** (which have the same reference numeral as the engaging protrusions **58R**).

The spindles **4R** and **4L** are long round bars made of a metal material, and a tapering process is performed on the leading ends **55R** and **55L** such that the leading ends are easily inserted into the insertion grooves **56R** and **56L**. In addition, the engaging portions **61R** and **61L** are provided integrally with the leading ends **55R** and **55L** on the rear side of the leading ends **55R** and **55L**, and are engaged with the engaged portions **57R** and **57L**, respectively, such that driving power is transmitted to the roll portion **31**. The engaging portions **61R** and **61L** include base portions **62R** and **62L** and flange portions **63R** and **63L** that come into contact with the outer end surfaces **54R** and **54L** of the roll retainers **5R** and **5L**, respectively. The base portions and the flange portions are integrally formed. The engaging portions **61R** and **61L** are rotated integrally with the spindles **4R** and **4L**, respectively.

The inner walls of the flange portions **63R** and **63L** that come into contact with the outer end surfaces **54R** and **54L** of the roll retainers **5R** and **5L** are defined as pressing reference surfaces **64R** and **64L**, respectively.

For example, three engaging ribs **66L** that extend in the axial direction and are engaged with the engaging protrusions **58L** of the driven roll retainer **5L** are provided on the outer circumferential surface of the base portion **62L** of the engaging portion **61L** of the driven spindle **4L** at the same pitch as that at which the engaging protrusions **58L** are arranged. Three cam grooves **59** that are engaged with the cam followers **58R**, serving as the engaging protrusions **58R**, of the driving roll retainer **5R** are formed on the outer circumferential surface of the base portion **62R** of the driving engaging portion **61R** at the same pitch as that at which the cam followers **58R** are arranged. The other portions of the driving base portion **62R** where the cam groove **59** is not formed serve as engaging convex portions **66R** that are engaged with the engaging protrusions **58R**.

The positioning mechanism **60** uses the moving mechanism **65** to support the roll sheet **P** with the spindles **4R** and **4L**, and rotates the roll portion **31** of the roll sheet **P** in a direction **X** in which tension is applied to the roll sheet **P**, thereby positioning the reference edge **E** of the roll sheet **P**. In this embodiment, the cam structure **60** (which has the same reference numeral as the positioning mechanism **60**) is a cylindrical cam including the cam followers **58R** and the cam grooves **59**, and forms the positioning mechanism **60**.

The cam groove **59** includes a guide portion **59A** that guides the entrance of the cam follower **58R** into the cam groove **59**, a drawing part **59B** that allows the cam follower **58R** to be drawn into the cam groove **59** such that the reference edge **E** of the roll sheet **P** reaches the regular position **S** when the roll portion **31** is rotated in the direction **X** in which tension is applied to the roll sheet **P**, and a straight portion **59C** that allows the cam follower **58R** to be withdrawn from the cam groove **59** when the roll portion **31** is rotated in a **Y** direction in which tension is removed. The guide portion **59A** includes two inclined planes having a shape that is tapered from one portion close to the leading end **55R** of the driving spindle **4R** to another portion close to the flange portion **63R**.

The drawing portion **59B** includes an inclined plane that is connected to the end of one of the two inclined planes that is

positioned in the direction **Y** in which tension is removed and has a tapered shape that is inclined downward toward the flange portion **63R**. In addition, a holding portion **67** that holds the cam follower **58R** at a set position is formed at the end of the drawing portion **59B** close to the flange portion **63R**. The straight portion **59C** includes a horizontal plane that is connected to the end of the other of the two inclined planes that is positioned in the direction **X** in which tension is applied and extends to the flange portion **63R**.

The spindle motor **30** is composed of a tension generating member **29** that generates a constant tension **F** to the roll sheet **P** between the transport roller **21** and the roll portion **31**. The set tension **F** of the roll sheet **P** is maintained at a constant value by controlling the set torque **T** of the spindle motor **30** to correspond to a variation in the roll diameter **D** or the roll radius **R** of the roll portion **31** of the roll sheet **P**. The spindles **4R** and **4L** and the spindle motor **30** form a roll rewinding mechanism **32**. The roll rewinding mechanism **32** is used to return the start point **33** of the roll sheet **P** drawn out in the drawing direction **A** during recording to the origin position, and applies tension to the roll sheet **P** between the transport roller **21** and the roll portion **31**.

The roll rewinding mechanism **32** basically includes: the spindles **4R** and **4L** that are rotatably supported in the horizontal direction by the supporting mechanisms **14R** and **14L**, respectively; the spindle motor **30** that is provided below the driving supporting mechanism **14R** positioned on the right side; and a gear train **36** that is provided between the driving spindle **4R** and an output shaft of the spindle motor **30**, reduces the rotational speed of the output shaft of the spindle motor **30**, and transmits the rotary power to the driving spindle **4R**.

The moving mechanism **65** includes a slider **68** that is provided below the driven supporting mechanism **14L** integrally with the supporting mechanism **14L** and a guide rail **69** that guides the movement of the slider **68** and extends in the roll width direction **C**. A holding portion **70** that holds the roll sheet **P** and an auxiliary concave portion **71** that facilitates the transport of the roll sheet **P** to the holding portion **70** are provided on the upper side and the front side of the guide rail **69**, respectively. The driving and driven supporting mechanisms **14R** and **14L** include, for example, two bearings **35R** and two bearings **35L** that rotatably support the driving and driven spindles **4R** and **4L**, and supporting frames **34R** and **34L** that support the bearings **35R** and **35L**, respectively.

In this embodiment, a shaft **37** protrudes from the rear surface of the spindle motor **30** and is rotated integrally with the spindle motor **30**. A disk-shaped detecting plate **39** having a plurality of slits **38** radially arranged at the same pitch is attached to the shaft **37**, and a detector **40** that detects the rotation angle **θ_2** of the spindle motor **30** using the slits **38** is provided in the vicinity of the detecting plate **39** in a non-contact state. The detecting plate **39** and the detector **40** form a rotary encoder **41**.

In addition, a disk-shaped detecting plate **44** having a plurality of slits **43** radially arranged at the same pitch is attached to a roll shaft **42** of the transport driving roller **19**, and a detector **45** that detects the rotation angle **θ_1** of the transport driving roller **19** using the slits **43** is provided in the vicinity of the detecting plate **44** in a non-contact state. The detecting plate **44** and the detector **45** form a rotary encoder **46**. In addition, a torque measuring unit **47** that measures the operation torque **Tr** of the transport driving roller **19** during a roll radius estimating process is provided in the vicinity of the transport driving roller **19**.

The transport device **1** for transmitting a roll-shaped recording medium according to this embodiment further

includes a torque control device **48** that controls the set torque T of the spindle motor **30** to correspond to a variation in the roll diameter D of the roll portion **31** such that a constant tension F is applied to the roll sheet P between the transport roller **21** and the roll portion **31**, regardless of the variation in the roll diameter D of the roll portion **31**.

The torque control device **48** includes: a static measurement unit **49** that measures the offset torque T_0 of the spindle motor **30** when a static load is applied; a tension setting unit **50** that sets the tension F of the roll sheet P on the basis of the operation torque Tr of the transport driving roller **19** and the roll radius r of the transport driving roller **19**; a roll radius estimating unit **51** that estimates the roll radius R of the roll sheet P on the basis of the rotation angle θ_2 of the spindle motor **30** and the rotation angle θ_1 of the transport driving roller **19** respectively detected by the two rotary encoders **41** and **46**, the roll radius r of the transport driving roller **19**, and the reduction ratio $1/N$ of the gear train **36**; and a torque setting unit **52** that sets the torque T of the spindle motor **30** such that the set tension F is maintained at a constant value, on the basis of the offset torque T_0 of the spindle motor **30** when a static load is applied, the tension F set by the tension setting unit **50**, the roll radius R estimated by the roll radius estimating unit **51**, and the reduction ratio $1/N$ of the gear train **36**.

Next, (A) a method of inserting or removing a roll-shaped recording medium using the transport device **1** for transporting a roll-shaped recording medium and (B) a process of setting the torque of a spindle motor according to this embodiment will be described.

(A) Method of Inserting or Removing Roll-Shaped Recording Medium

(1) Process of Supporting Roll Portion (see FIGS. 4 and 9A)

The moving mechanism **65** moves the driven supporting mechanism **14L**, and the driven roll retainer **5L** moves a set roll sheet P toward the driving spindle **4R** to set the driving roll retainer **5R** to the driving spindle **4R**. Specifically, the driven supporting mechanism **14L** is moved integrally with the slider **68** toward the driving spindle **4R** along the guide rail **69** to insert the leading end **55R** of the driving spindle **4R** into the insertion groove **56R** of the driving roll retainer **5R** and insert the base portion **62R** of the driving spindle holder **61R** into the engaged portion **57R**.

In this process, the outer end surface **54R** of the driving roll retainer **5R** may not necessarily come into contact with the pressing reference surface **64R** that is formed on the flange portion **63R** of the driving spindle holder **61R**. As shown in FIG. 9A, the cam follower **58R** inserted into the cam groove **59** is guided by the inclined planes of the guide portion **59A** and passes through at least a connecting portion between the guide portion and the drawing portion **59B**.

(2) Set Position Correcting Process (see FIG. 9B)

A set position correcting process moves the roll portion **31** of the roll sheet P in the direction X in which tension is applied to the roll sheet to correct the set position of the roll sheet P , and moves the reference edge E of the roll sheet P to a regular position S . Specifically, any of the following general operations is performed: an operation of supporting the roll sheet P with two spindles and drawing out the start point **33** of the roll sheet P from the roll portion **31**; an operation of rotating the transport roller **21** to transport the roll sheet P in the drawing direction A during recording; and an operation of rotating the driving spindle **4R** in a winding direction B in order to apply tension to the roll sheet P between the transport roller **21** and the roll portion **31** before recording.

During the general operations, the driving spindle **4R** and the driving engaging portion **61R** are certainly rotated in the direction X in which tension is applied. Then, as shown in

FIG. 9B, the cam follower **58R** is guided by the inclined plane of the drawing portion **59B** and reaches the holding portion **67** that comes into contact with the pressing reference surface **64R** of the flange portion **63R**. When the cam follower **58R** reaches the holding portion **67**, the reference edge E of the roll sheet P is disposed at the regular position S .

(3) Set Position Releasing Process (see FIG. 9C)

A set position releasing process rotates the roll portion **31** of the roll sheet P in the direction Y in which tension is removed such that the roll sheet P maintained at the set position can be moved to a driven side. That is, when the cam follower **58R** shown in FIG. 9B is held by the holding portion **67**, the drawing portion **59B** that is inclined upward prevents the cam follower **58R** from being moved to the driven side. Therefore, as shown in FIG. 9C, the roll sheet P is rotated in the direction Y in which tension is removed. Then, the cam follower **58R** is moved upward due to its appearance. In FIG. 9C, the cam follower comes into contact with the straight portion **59C** that is positioned above the cam follower. In this state, the cam follower **58R** can be guided by the straight portion **59C** to be smoothly moved. Therefore, it is possible to easily release the position of the roll sheet P set at the driving side.

(B) Process of Setting Torque of Spindle Motor

FIG. 11 is a flowchart illustrating the first half of a control process of setting the torque of the spindle motor, and FIG. 12 is a flowchart illustrating the second half of the control process.

Next, the process of setting the torque of the spindle motor **30** is divided into four processes, such as (1) a static measurement process, (2) a tension setting process, (3) a roll radius estimating process, and (4) a torque setting process. The four processes will be described with reference to the flowcharts.

(1) Static Measurement Process (see FIG. 11)

A user sets the roll sheet P to the spindles **4R** and **4L** in Step S1. Specifically, the user attaches the roll retainers **5R** and **5L** to both sides of the roll sheet P , and sets the roll retainer **5L** to the spindle **4L** first. Then, the user moves the roll sheet P from the spindle **4L** to the spindle **4R** to set the roll retainer **5R** to the spindle **4R**. Then, in Step S2, the user performs a predetermined recording setting operation and issues a recording instruction.

Then, in Step S3, the transport driving roller **19** is rotated backward to loosen the roll sheet P between the transport roller **21** and the roll portion **31**. Then, in Step S4, it is selected whether to rotate the roll sheet P forward to perform static measurement in the forward direction or to rotate the roll sheet P backward to perform static measurement in the backward direction. Basically, in Step S5, the roll sheet P is rotated forward, and in Step S7, the offset torque T_0 of the spindle motor **30** that is rotated forward when a static load is applied is measured.

When it is selected to perform static measurement in the backward direction, the roll sheet P is rotated backward in Step S6, and the offset torque T_0 of the spindle motor **30** that is rotated backward when a static load is applied is measured in Step S7. However, the offset torque T_0 is measured on the basis of a current value required to rotate the spindle motor **30** forward or backward.

(2) Tension Setting Process (see FIG. 11)

Then, in Step S8, the roll sheet P is loosened, and in Step S9, the transport driving roller **19** is rotated forward. Then, in Step S10, the operation torque Tr of the transport driving roller **19** is measured by the torque measuring unit **47**, and in Step S11, the rotation angle θ_1 of the transport driving roller **19** is measured by the rotary encoder **46**. In Step S12, the set tension F is calculated from the relationship $F=Tr/r$ on the

11

basis of the measured operation torque T_r of the transport driving roller 19 and the known roll radius r .

In Step S13, a feed L per revolution is calculated from the relationship $L=r\theta_1$ on the basis of the detected rotation angle θ_1 of the transport driving roller 19 and the known roll radius r . Then, in Step S14, it is determined whether the roll sheet P makes one revolution. If it is determined that the roll sheet makes one revolution, the next roll radius estimating process is performed. If it is determined that the roll sheet does not make one revolution, the process returns to Step S3 to repeatedly perform the measurement of the offset torque T_0 and the calculation of the set tension F and the feed L per revolution.

When the operation torque T_r of the transport driving roller 19 is constant, the tension setting process is omitted, and tension is appropriately selected from a table having tension data set for each sheet type and each sheet width.

(3) Roll Radius Estimating Process (see FIG. 12)

Then, in Step S15, it is determined whether the calculated set tension F is less than a predetermined reference tension F_0 . If $F < F_0$, the minimum value of the measured offset torque T_0 is selected in Step S16. On the other hand, if $F \geq F_0$, the average value of the measured offset torque T_0 is selected in Step S17. F_0 is a reference tension corresponding to the roll sheet P .

In Step S18, the rotation angle θ_2 of the spindle motor 30 is detected by the rotary encoder 41. In Step S19, the roll radius R of the roll portion 31 is estimated from the relationship $R=(L/\theta_2)\cdot N$ on the basis of the feed L per revolution calculated in Step S13, the rotation angle θ_2 of the spindle motor 30 detected in Step S18, and the known reduction ratio $1/N$ of the gear train 36.

(4) Torque Setting Process (see FIG. 12)

Then, in Step S20, the torque T of the spindle motor 30 is set from the relationship $T=(F\cdot R - T_0)/N$ on the basis of the offset torque T_0 measured in Step S7, the set tension F calculated in Step S12, the roll radius R estimated in Step S19, and the known reduction ratio $1/N$. In Step S21, recording is performed by a constant tension F caused by the set torque T , without being affected by a variation in the roll diameter D .

Other Embodiments

The transport device 1 for transporting a roll-shaped recording medium and the recording apparatus 100 including the transport device 1 for transporting a roll-shaped recording medium according to this embodiment of the invention have the above-mentioned structure as the basic structure, and the structure may be partially changed or omitted without departing from the scope and spirit of the invention.

For example, the positioning mechanism is not limited to the cam structure 60 according to the above-described embodiment, but a screw structure that uses a nut as the engaged portion 57R of the driving roll retainer 5R and a bolt as the driving spindle holder 61R may be used as the positioning mechanism. In addition, the shape of the cam groove 59 is not limited to the above-described embodiment, but the cam groove 59 may have various shapes as long as it can obtain the same operations and effects as described above. The cam follower 58R may be provided in the spindle holder 61R, and the cam groove 59 may be formed in the roll retainer 5R.

Further, the tension generating member 29 is not limited to the spindle motor 30, but it may be other electromotive motors, or an electromagnetic clutch or brake. The output shaft of the spindle motor 30 may be directly connected to the

12

driving spindle 4R without the gear train interposed therebetween as long as the spindle motor 30 can be rotated at a low speed.

5 What is claimed is:

1. A transport device for transporting a roll-shaped recording medium, comprising:

a pair of roll retainers that are attached to both sides of a roll portion of the roll-shaped recording medium;

a pair of spindles that are engaged with the roll retainers to support the roll portion;

a transport roller that transports the roll-shaped recording medium drawn out from the roll portion while pinching the roll-shaped recording medium; and

a positioning mechanism that includes a drawing portion which rotates the roll portion supported by the spindles and draws the roll portion towards the spindles such that a reference edge on the side of the roll-shaped recording medium comes into contact with a reference position on the spindle, thereby positioning the reference edge of the roll-shaped recording medium.

2. The transport device for transporting a roll-shaped recording medium according to claim 1, further comprising: a tension generating unit that generates a constant tension to the roll-shaped recording medium between the transport roller and the roll portion, regardless of a variation in the roll diameter of the roll portion.

3. A recording apparatus comprising:

the roll-shaped recording medium transport device according to claim 1 that transports a roll-shaped recording medium to a recording position while drawing out the roll-shaped recording medium; and

a recording device that ejects ink onto a recording surface of the roll-shaped recording medium transported to the recording position to perform desired recording.

4. A transport device for transporting a roll-shaped recording medium, comprising:

a driving roll retainer and a driven roll retainer that are attached to both sides of a roll portion of the roll-shaped recording medium;

a driving spindle and a driven spindle that are engaged with the driving roll retainer and the driven roll retainer to support the roll portion;

a driving supporting mechanism and a driven supporting mechanism that support the driving spindle and the driven spindle;

a spindle driving source that rotates the driving spindle forward and backward;

a moving mechanism that moves the driven supporting mechanism toward the driving supporting mechanism such that the driving spindle and the driven spindle support the roll portion;

a transport roller that transports the roll-shaped recording medium drawn out from the roll portion while pinching the roll-shaped recording medium; and

a positioning mechanism drawing the roll portion toward the driving spindle and the driven spindle that positions a reference edge of the roll-shaped recording medium by operating the transport roller or the spindle driving source or drawing out the roll-shaped recording medium from the roll portion to rotate the roll portion supported by the driving spindle and the driven spindle, the drawing portion thereby moving and drawing the roll portion toward the driving spindle such that the reference edge on the side of the roll-shaped recording medium comes into contact with a reference position on the driving spindle.

13

5. The transport device for transporting a roll-shaped recording medium according to claim 4, further comprising: engaging portions that are provided in the driving spindle and the driven spindle; and engaged portions that are provided in the driving roll retainer and the driven roll retainer and are engaged with the engaging portions of the driving and driven spindles such that power can be transmitted, wherein the positioning mechanism is a cam structure that is provided between the engaged portion of the driving roll retainer and the engaging portion of the driving spindle. 10
6. The transport device for transporting a roll-shaped recording medium according to claim 5, wherein the cam structure has a cam including a cam follower that is formed on an inner circumferential surface 15

14

of the driving roll retainer so as to extend inward and a cam groove that is formed in an outer circumferential surface of the engaging portion, and the cam groove includes: a guide portion that guides the cam follower into the cam groove; a drawing portion that draws the cam follower into the cam groove such that the reference edge of the roll-shaped recording medium reaches the reference position when the roll portion is rotated in the direction in which tension is applied; and a straight portion that enables the cam follower to be withdrawn from the cam groove when the roll portion is rotated in a direction in which the tension is removed.
